UNITED STATES PATENT OFFICE.

PHILIPPE BALDENSPERGER, OF ST. PIÉ, (VOSGES,) FRANCE.

MANUAL MOTOR.

SPECIFICATION forming part of Letters Patent No. 486,020, dated November 8, 1892.

Application filed March 24, 1892. Serial No. 426,281. (No model.) Patented in France April 30, 1891, No. 212,173; in Belgium July 27, 1891, No. 95,789; in Sweden July 29, 1891, No. 3,412; in Norway August 3, 1891, No. 2,473; in Italy August 8, 1891, XXV, 30,175, and November 6, 1891, XXV, 30,559; in Spain August 31, 1891, No. 12,392; in Turkey September 26, 1891, No. 240; in Switzerland October 2, 1891, No. 3,907; in Russia October 9, 1891; in Austria-Hungary October 11, 1891, No. 48,974 and No. 552; in England October 12, 1891, No. 17,352, and in Germany October 14, 1891, No. 66,479.

To all whom it may concern:

Be it known that I, PHILIPPE BALDENS-
PERGER, a citizen of the Republic of France,
residing at St. Pié, (Vosges,) France, have in-
5 ventioned an Improved Manual Motor, (for which
I have obtained the following patents: in
France April 30, 1891, No. 212,173; in Bel-
gium July 27, 1891, No. 95,789; in Great Brit-
ain October 12, 1891, No. 17,352; in Austria-
10 Hungary October 11, 1891, No. 48,974 and No.
552; in Germany October 14, 1891, No. 66,479;
in Spain August 31, 1891, No. 12,392; in Italy
August 8, 1891, XXV, 30,175, and (addition)
November 6, 1891, XXV, 30,559; in Norway
15 August 3, 1891, No. 2,473; in Sweden July 29,
1891, No. 3,412 and (patent) (addition) Octo-
ber 23, 1891, No. 3,412; in Russia October 9,
1891; in Turkey September 26, 1891, No. 240,
and in Switzerland October 2, 1891, No. 3,907,)
20 of which the following is a specification.

This invention has reference to motors de-
signed to be actuated by manual effort; and
it consists in the simple and efficient arrange-
ment hereinafter described, whereby a com-
paratively-high degree of power is created
25 with but minimum exertion.

In the accompanying drawings, forming
part of this specification, Figure 1 is a cen-
tral vertical section of a manual motor em-
30 bodying my improvement, and Fig. 2 is a front
view of the same.

The base of the motor-frame comprises two
triangular castings S, forming bearings for
the transverse shaft O, upon one of the pro-
35 jecting ends of which is keyed a band-pulley
V, which may operate a belt to drive any de-
sired machinery. The base-castings S are
braced at their top by a transverse rod b, and
the upper part of the framing is constituted
40 by two vertical standards e, connected and
braced at their top by a transverse bar f.
Centrally keyed on the transverse shaft O is
a ratchet-wheel R, the teeth of which are en-
gaged by pawls B B', pivotally carried by two
45 arms K K, loosely mounted at one end on the

shaft O, while the other ends are pivotally
secured to links c and c', in turn pivotally
bolted to the lower end of the vertical lever
a. The lever a is fulcrumed upon a rod h,
bearing in a pair of arms D, rigidly project-
50 ing from the upper portion of the base-cast-
ing S. The saddle A has a sleeve E, loosely
mounted on an upper rod f, and depending
extension F of said sleeve being pivotally
connected at g, to the lever a through the me-
55 dium of a link connection C. The upper end
of the lever a is provided with transverse
handles M, and the arms D are provided with
a transverse foot-piece P.

The operation of this device will be obvious.
The operator, seated in the saddle A, rigidly
braces his feet against the foot-piece P and
can then vibrate the lever a with compara-
tively-little exertion, the movements of the
lever a in either direction occasioning the ro-
55 tation of the ratchet-wheel, and the conse-
quent revolution of shaft O and band-pulley
V, since the pawls B and B' alternately en-
gage said ratchet-wheel, and both serve to ro-
tate it in a like direction. By having the sad-
60 dle A pivoted and connected, as described, the
exertion on the part of the operator is not
only materially reduced, but much is taken off
of body movements to secure the actuation
of the device.

I claim—

1. In a manual-motor apparatus, the com-
bination, with the supporting-frame, a driv-
ing-shaft journaled therein, and a ratchet-
wheel carried thereby, of rod h, an actuating-
80 lever pivoted thereto, a pair of arms pivoted
to one end of said lever, pawls thereon adapt-
ed to engage with the teeth of said ratchet-
wheel, and a saddle pivotally mounted on the
main frame and having a link connection 85
with the actuating-lever, substantially as set
forth and described.

2. In a manual-motor apparatus, the com-
bination, with the driving-shaft and pawl-
and-ratchet devices located in the base of the 90

apparatus, of arms D-D, having the foot-rest
P, and rod *h*, and an actuating-lever *a*, pivot-
ed on said rod and connected with the pawl
devices, together with a pivotally-mounted
5 saddle having a link connection with the said
lever above its fulcrum, substantially as set
forth.

In testimony whereof I have signed this
specification in the presence of two subscrib-
ing witnesses.

PHILIPPE BALDENSPERGER.
